UNITED STATES PATENT OFFICE.

FRANK E. SAGENDORPH, OF CHICAGO, ILLINOIS, ASSIGNOR OF ONE-HALF TO
E. STARR LLOYD, OF SAME PLACE.

SHEET-METAL ROOFING.

SPECIFICATION forming part of Letters Patent No. 416,687, dated December 3, 1889.

Application filed October 4, 1889. Serial No. 326,018. (No model.)

To all whom it may concern:

Be it known that I, FRANK E. SAGENDORPH, of Chicago, in the county of Cook and State of Illinois, have invented certain new and useful Improvements in Sheet-Metal Roofing, of which the following is a clear, full, and exact description, reference being had to the accompanying drawings, forming a part of this specification, in which—

10 Figure 1 is a side elevation of a portion of a building, showing a sheet-metal roof applied thereto embodying the features of my invention. Fig. 2 is a perspective view in detail of a portion of the adjacent metal sheets, including the standing seam and fastening device. Fig. 3 is an end view of the same as it appears when on an inclined roof. Fig. 4 is a perspective view of the same looking toward the opposite side of the standing seam from that shown in Fig. 2. Fig. 5 is a perspective view in detail of a portion of one of the roof-sheets, showing the position of one of the fastening-cleats when partially adjusted in position. Fig. 6 is a like view from the opposite 25 side of the seam, showing a step further in the process of adjustment of the cleat. Fig. 7 is an end view of the same, showing the adjacent sheet placed in position ready to be secured by the fastening-cleat. Fig. 8 is a perspective view of one of the fastening-cleats, and Fig. 9 is a like view of a modification thereof.

Corresponding letters of reference in the different figures designate like parts. 30 My invention has reference to that class of sheet-metal roofs in which the adjacent metallic sheets are attached to each other by means of what are commonly known as "standing seams;" and my object is to so construct 35 and attach a cleat or fastening that it may be placed in position upon the flange of a given sheet and nailed to the roof before the adjustment of the next succeeding sheet, after which it may be bent thereover to lock said 40 last-named sheet thereto.

My invention therefore consists in the construction of the cleat and the combination thereof with the standing seam of a sheet-metal roof, substantially in the manner hereinafter more particularly described and claimed.

Referring to the drawings, A, Fig. 1, represents the building, B the roof-frame, and C the sheet-metal roofing-plates attached thereto. In order to designate the adjacent sheets 55 in the other figures, so as to describe their mode of attachment and avoid confusion, I have designated the plate upon the right by means of the letter C'. Assuming that the sheets are laid from left to right, as is the 60 usual practice, a double flange $c c'$ is formed upon the right-hand edge of the sheet, the flange c' being only about half the width of the flange c .

My improved cleat D, which is formed from 65 a single piece of sheet metal split at d , and provided by preference with a short perforated strip d' and a longer strip d^2 , is attached to the sheet C by bending its broad end d^3 upwardly at about the beginning of the cut 70 d and inserting the said portion between the flanges $c c'$, as clearly shown in Fig. 5, when the part d' is nailed to the roof, as shown at d^4 , Figs. 5, 6, and 7. The part d^2 is thence bent upwardly around the flange c' , as shown in 75 Fig. 5, and thence downwardly, as shown in Figs. 6 and 7. All of the cleats throughout the length of the roof being thus placed, nailed, and bent at proper distances from each other, as shown at the right in Fig. 1, the next 80 sheet C', which is provided with corresponding flanges $c^2 c^3$, is then placed in position with the flanges $c^2 c^3$ overlapping the vertical flanges $c c'$ and that portion of the part d^2 which is bent over the flanges $c c'$, as 85 stated. This stage of the construction is clearly shown in Fig. 7. The remaining portion of the part d^2 in each of the cleats D is then bent upwardly and over the flanges $c^2 c^3$, as shown in Figs. 1 to 4, inclusive, and indicated in dotted lines in Fig. 7, thereby locking 90 the adjacent sheets firmly together, while opportunity is afforded for the free expansion and contraction of the metal.

I prefer in constructing the cleat D to form 95 a double crimp therein, as shown at d^5 , Figs. 7 and 9. This imparts great strength to the cleat and prevents it from tearing when the parts $d^1 d^2$ are drawn in opposite directions.

The advantages derived from using my improved cleats are that they may be placed in position and the seam compressed with crimp-

ing-tongs before nailing the cleat and afterward placing the adjacent sheet in position. This cannot be accomplished in constructions heretofore employed without loosening the 5 cleat from the roof. Another advantage is that a roof may be laid much more rapidly when my improved cleats are employed than if they were not used.

Having thus described my invention, I 10 claim—

1. The combination, with the vertical flanges comprising the standing seam of a sheet-metal roof, of a split cleat having one of its members or strips attached to the roof- 15 boards, its base or wide end inserted between the inner vertical flanges of one sheet, and the other member bent outwardly around said flange and thence outwardly over and around the overlapping flange of the adjacent sheet,

whereby the adjacent sheets are locked to each 20 other and attached to the roof-frame, substantially as shown and described.

2. The combination, with the vertical flanges $c c'$ and $c^2 c^3$ of the adjacent sheets of a sheet-metal roof, of the split cleat D, se- 25 cured to the roof-frame and bent and interlocked, as described, substantially as speci- fied.

3. The cleat D, provided with strips or tongues $d' d^2$ and the doubled-crimped part 30 d^5 , substantially as shown and described.

In testimony whereof I have signed this specification, in the presence of two subscr- 25
ing witnesses, this 23d day of September, 1889.

FRANK E. SAGENDORPH.
